UNITED STATES PATENT OFFICE.

WILLIAM WALLACE WOTHERSPOON, OF NEW YORK, N. Y.

METHOD OF TESTING CHAMBERS, &c., FOR LEAKS.

1,202,347.

Specification of Letters Patent.

Patented Oct. 24, 1916.

Application filed February 8, 1912. Serial No. 676,310.

To all whom it may concern:

Be it known that I, WILLIAM WALLACE WOTHERSPOON, a citizen of the United States, residing at New York, in the county of New York and State of New York, have invented certain new and useful Improvements in Methods of Testing Chambers, &c., for Leaks, of which the following is a specification, reference being had therein to the accompanying drawing.

This invention relates to a method of testing chambers or vessels in order to ascertain if a leak opening exists, such tests being desirable in connection with various fluid-containing chambers, such as steam boilers, water tanks, water-tight compartments of ships, ships' double bottoms, and the like.

In the case of water-tight compartments of ships, it is of vital importance that the compartments be free from leaks, so that when occasion arises, as when a hole is stove in one or more compartments, the closure of the uninjured compartments, will effectually check the danger of the water finding its way beyond the injured compartment.

In accordance with my invention, I propose in testing for a leak opening in chambers or compartments, to force air under pressure into the same, after first closing the usual and ordinary communications of the compartment or chamber with the outside, and I provide for the entrance of a workman into the chamber while the pressure is maintained. While in the chamber the workman will be enabled to determine, either by visible or audible signs, if there is any escape of air, such signs being far more noticeable from within the chamber than from without.

In the accompanying drawings I have shown the practice of my improved method in connection with steam boiler, to test the same for leaks, and the figure of the drawing represents in perspective, with parts in section, a steam boiler equipped with an air lock, and connected with a suitable source of compressed air.

Referring to the drawings, A represents a boiler having applied to the manhole B, an air lock C, having the usual doors D and E and valves F and F'.

G represents an air compressor, and H a pipe leading from the compressor and entering the boiler.

In making the test in accordance with my invention, the door E is closed and the valve

F shut off, and air is forced into the boiler under suitable pressure. The workman enters the lock through door D and closes the same after him, and closes also valve F'. Next he opens valve F so that the pressure in the boiler and lock chamber will equalize, whereupon door E is opened and the workman enters the boiler. In making the test to determine if there is any opening through which the compressed air is escaping, several different expedients may be resorted to. First, by listening to hear for the escape of the air. If the smallest leak opening exists, the air under pressure within the chamber will escape through the opening with a hissing sound, which, by reason of the fact that the air in passing through the opening is rushing from all points under pressure, and further by reason of the fact that all outside sounds are shut out, will be clearly heard, and the exact location of the opening enabled to be found. Second, by the use of a torch or candle moved around the interior of the chamber. Any escape of air will at once deflect the flame in the direction of the opening, and will offer clear and unmistakable evidence if a leak exists. Third, by the use of a powder or dust thrown into the air. If there is a leak, the particles will flow in a stream toward the same. Smoke may be also employed in this manner and with the same effects.

Other means unnecessary to here mention, may be resorted to, the foregoing expedients being those which at the present time occur to me, and all of them being particularly available for the purposes in view, by reason of the fact that they are of peculiar effectiveness when practised inside the chamber while the pressure of air therein is maintained.

While in the foregoing description it is set forth that the workman enters the chamber after the air has been forced under pressure therein, it will be manifest that the invention comprehends as well a method of procedure under which the air pressure may be put on after the workman has entered. However, the former course is preferable by reason of the ease of making an entrance into the chamber by means of an air lock.

Having thus described my invention, what I claim is:—

The method of testing chambers, compartments, and the like, for the detection of leak openings, which consists in closing air-

tight the usual and ordinary communications of the chamber with the outside, introducing air under pressure into the closed chamber, distributing an indicating medium within the chamber capable of being displaced by air currents, and finally locating the position of the leak by observing within the chamber the direction of flow of said in-

dicating medium toward the leak opening under the influence of the escaping air. 10

In testimony whereof I affix my signature in presence of two witnesses.

WILLIAM WALLACE WOTHERSPOON.
